United States Patent Office

Des. 209,931
Patented Jan. 16, 1968

209,931

BOTTLE

Alfred D. Sterges, Los Angeles, Calif., assignor to Purex Corporation, Ltd., Lakewood, Calif., a corporation of California

Filed Jan. 3, 1967, Ser. No. 5,277

Term of patent 14 years

(Cl. D58—8)

FIG. 1.

FIG. 2.

FIG. 3.

FIG. 1 is a front elevation view of a bottle embodying my new design;

FIG. 2 is a top view thereof; and

FIG. 3 is a bottom view thereof.

The dominant features of my design reside in the portions shown in full lines.

I claim:

The ornamental design for a bottle, substantially as shown and described.
